(57) CLAIM

The ornamental design for a disposable eyeshade with adhesive, as shown and described.

DESCRIPTION

FIG. 1 is a three-quarter perspective view of the face side of a disposable eyeshade with adhesive showing my new design.

FIG. 2 is a front plan view thereof.

FIG. 3 is a side-end plan view thereof.

FIG. 4 is a back plan view thereof.

FIG. 5 is a top-end plan view thereof; and,

FIG. 6 is a bottom-end plan view thereof.

The stippling shown on the disposable eyeshade is understood to represent the adhesive.
